PROCESS OF CRACKING PETROLEUM HYDROCARBONS

Filed May 3, 1927

UNITED STATES PATENT OFFICE

ALFRED M. HOUGHTON, OF WASHINGTON, DISTRICT OF COLUMBIA, ASSIGNOR TO GULF ⁶¹
REFINING COMPANY, OF PITTSBURGH, PENNSYLVANIA, A CORPORATION OF TEXAS

PROCESS OF CRACKING PETROLEUM HYDROCARBONS

Application filed May 3, 1927. Serial No. 188,490.

This invention relates to improvements in processes of cracking petroleum hydrocarbons; and comprises cleaning the draw-off line of a cracking still by admitting to the still 5 through the draw-off line a portion of the oil either on its way to the cracking zone or immediately after it has passed the cracking zone; all as more fully hereinafter set forth and as claimed.

10 Oil cracking processes now in use to a large extent involve heating the heavier hydrocarbon to be cracked in one zone, delivering the heated products to another zone, removing and condensing vapors from the second zone 15 and removing heavy uncracked oil and tarry residual petroleum hydrocarbons from the second zone. Sometimes the oil is heated in the first zone under conditions whereby there is substantially no conversion and is then 20 delivered to the second zone and maintained there as a body of oil while conversion takes place. In such a process there results a large amount of heavy tarry and asphaltic hydrocarbons which gradually accumulate 25 and which tend to clog the draw-off pipe. In one process now in use to a large extent the oil is heated in the first zone to a cracking and vaporization temperature and there substantially vaporized and con- 30 verted and the products of such heating are delivered to a separating chamber from which the vapors are removed and from which residual oil is removed substantially as fast as it accumulates. In this process there 35 is a tendency for the draw-off line to become clogged by heavy hydrocarbons and asphaltic matter which acts as a binder. Attempts have been made to keep the draw-off line clear of accumulation of the residue by me- 40 chanical scraping devices and the like but these are not eminently successful due to inherent disadvantages in the operation of a mechanical device inside a pipe where high pressures prevail.

45 In accordance with my invention the oil from the heating zone is delivered to the sec-
ond zone in one of the known ways and the draw-off pipe from the second zone is kept open for continuous withdrawal of residue.
50 After a time when there is a tendency for

the draw-off pipe to clog, which may be ob-
served by test samples drawn from time to
time, the oil or part of it from the first heat-
ing zone is caused to travel to the second zone
through the draw-off pipe. This oil being hot
and under high pressure and traveling at a
considerable rate of speed forces out accumu-
lation of solid and tarry matters in the draw-
off pipe and causes them to mingle with any
oil in the second zone. A minute or so of such
purging the draw-off pipe is usually sufficient,
whereupon the normal process is resumed.
Should the clogging of the draw-off pipe be
occasioned by an undue accumulation of as-
phalt binder this may be dissolved more read-
ily by a distillate which has not undergone
any substantial conversion and therefore I
may force through the draw-off line and
into the second zone some of the charge oil
before it has reached and passed through the
first heating zone, this charge oil containing
a quantity of reflux condensate.

The accompanying illustration shows one
form partly in section and partly in eleva-
tion of a cracking unit in which my process
may be performed.

In the drawing 1 indicates the furnace
heated by means of oil burners located at 2
and having mounted therein a coil 3 to which
the oil to be cracked is supplied. This oil
may comprise charge oil which has been used
to scrub outgoing vapors from the second
zone, as will be hereinafter described. The
heated oil passes from the coils 3 by means
of line 4 to the chamber 5 which is provided
with the dephlegmator 6, baffle plates 7, and
inlet for charge oil 8. At a low point the
chamber is provided with continuous draw-
off line 10 having continuation 10A. Vapors
from the dephlegmator are delivered by line
13 to the final condenser. The charge oil
after scrubbing the vapors arising in the sep-
arating chamber is delivered together with
condensate by means of trap 11 and line 12
to the inlet of the cracking coils by means
of pump 12—A. Pressure may be main-
tained past the reflux condenser or past the
final condenser 9 by means of the valves 14
and 15 respectively and, if desired, the pres-
sure may be released before the oil is deliv- 100

ered from the first zone to the separating chamber.

In addition to the connections described I provide a valved line 17 leading from the discharge or cracking coils to the draw-off line. Also in addition to the charge line leading to the zone of heating I provide a line 18 communicating the charge line with the tar draw-off. These lines are properly valved so that 10 some or all of the highly heated oil from the heating zone may be sent through the draw-off line into the chamber or some or all of the charge oil may be sent through the draw-off line into the chamber. 19 indicates a sample line which may be used from time to time for the purpose of observing the character of the draw-off and 20 indicates the charge line which may be used at the beginning of an operation for filling the system.

20 Clogging of the draw-off line is due to a large extent to a thickening or solidification of asphaltic or tarry hydrocarbons acting as a binder for the carbon; the thickening or solidification being incident to a drop in temperature between the cracking zone proper and the separation chamber. By adding hot oil of the same character, this thickening or solidification is obviated and the whole mass is made mobile enough for removal.

30 What I claim is:

1. In an oil cracking process in which the oil is heated in one zone and delivered to a second zone from which heavy residue is withdrawn through a draw-off line, the step 35 which comprises cleaning the draw off line by intermittently forcing therethrough into the second zone some of the cracked oil directly from the first zone.

2. In an oil cracking process in which the oil is heated in one zone and delivered to a second zone from which heavy residue is withdrawn through a draw-off line, the improvement which comprises, during the cracking process, intermittently forcing 45 through the draw-off line in a direction opposed to the normal draw-off, a quantity of the oil immediately as it leaves the first zone.

3. In an oil cracking process in which the oil is heated in one zone and delivered to a second zone from which heavy residue is withdrawn through a draw-off line, the improvement which comprises intermittently, during the cracking process, forcing through the draw-off line in a direction opposed to the 50 normal draw-off, a quantity of oil directly from the first zone.

In testimony whereof, I have hereunto affixed my signature.

ALFRED M. HOUGHTON.
